(57) **CLAIM**

We claim the ornamental design for the electronic data processing equipment cabinet, as shown.

DESCRIPTION

FIG. 1 is a front, top and side perspective view of an electronic data processing equipment cabinet showing our new design;

FIG. 2 is a rear, top, and side perspective view thereof;

FIG. 3 is a front elevational view thereof;

FIG. 4 is a rear elevational view thereof;

FIG. 5 is a right side elevational view thereof;

FIG. 6 is a left side elevational view thereof; and,

FIG. 7 is a top plan view thereof.
